United States Patent Office

Des. 197,281
Patented Jan. 7, 1964

197,281

EXECUTIVE TYPE TELEPHONE STAND

Henry Dreyfuss, South Pasadena, Calif., and Cornelius Tanis, Colts Neck, N.J., assignors to Bell Telephone Laboratories, Incorporated, New York, N.Y., a corporation of New York

Filed Nov. 13, 1962, Ser. No. 72,446

Term of patent 14 years

(Cl. D26—14)

FIG. 1

FIG. 2

FIG. 3

FIG. 1 is a perspective view of an executive type telephone stand showing our new design;

FIG. 2 is a plan view of the executive type telephone stand shown in FIG. 1; and

FIG. 3 is a side elevational view of the executive type telephone stand shown in FIG. 1.

The dominant features of our new design reside in the portion shown in solid lines on the drawing.

We claim:

The ornamental design for an executive type telephone stand, as shown and described.
